2 SHEETS—SHEET 2.

UNITED STATES PATENT OFFICE.

SIMON NAGER, JR., OF ROCKVILLE CENTER, NEW YORK.

AUTOMATIC TAPE-STRIP PRINTING AND DISPENSING DEVICE.

1,193,589.

Specification of Letters Patent. Patented Aug. 8, 1916.

Application filed December 29, 1914. Serial No. 879,491.

To all whom it may concern:

Be it known that I, SIMON NAGER, Jr., a citizen of the United States, and a resident of Rockville Center, in the county of Nassau and State of New York, have invented a new and Improved Automatic Tape-Strip Printing and Dispensing Device, of which the following is a full, clear, and exact description.

My invention relates to a device for printing, moistening and cutting automatically, strips of tape unwound from a gummed roll of tape.

An object of the invention is to provide a simple, strong, compact, inexpensive and automatic machine, which is neat in appearance, which is easy to manipulate and in which rolls of gummed tape can be easily and quickly interchanged.

Another object of the invention is to provide a tape printing and moistening device in which the strip of tape delivered, can be picked up without touching the moistened, gummed surface of the strip.

A further object of the invention is to provide a device in which tape of different widths can be used, without any alteration or changes in the device.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a longitudinal vertical section of my device; Fig. 2 is a transverse section on the line 2—2, Fig. 1; Fig. 3 is a horizontal section on the line 3—3, Fig. 1; Fig. 4 is a fragmentary view of the strip-carrying mechanism, showing the same at the moment of cutting off the strip; Fig. 5 is a similar view, showing the strip-cutting mechanism in a different position; and Fig. 6 is a diagrammatic view, showing the printing mechanism in a different position from that shown in the preceding figures.

Referring to the drawings, 7 represents a base of any suitable material, to which is rigidly secured, a frame 8, the side 9 of which extends above the other side 10 of the frame. Mounted in the upper central part of the side 9, is a fixed axle 11, to which a spider 12 is attached adjacent the side 9. Another spider 13 is removably attached to

the axle 11 at the free end thereof. Between the spiders 12 and 13, a roll of tape 14 is mounted on the axle 11, and in accordance with the width of the tape used, the distance between the spiders 12 and 13 will vary. The purpose of the spiders is to prevent any lateral displacement of the roll on the axle 11. Mounted between the frame sides 9 and 10, is a roller 15, positioned far enough below the axle 11, so as not to interfere with the largest roll of tape that can be mounted on the said axle 11. The roller 15 is preferably flanged at one end, to guide the tape 16 coming from the roll 14 about said roller 15, back to the roll 14.

Co-acting with the roller 15, is a printing roller 17, for which the roller 15 forms a support. The said printing roller is removably associated with the ends of a pair of pivotal arms 18, the other end of each of said arms 18 being engaged by a bolt 19, pivotally connected to a resilient member 20 attached to the base. The resilient members 20 permit a variation of pressure on the rollers 15, by the printing roller 17 through the medium of the bolts 19.

Mounted between the sides of the frame adjacent the printing roller, is an inking device, consisting of an ink-transferring roller 21, in contact with the printing roller 17 and an ink-carrying roller 22. Another roller 23 contacts with the ink-carrying roller to uniformly distribute on the outer surface thereof, the ink passing from the inside of the ink-carrying roller to the outside thereof. All of said rollers are mounted in facing slots 24, provided in the frame sides 9 and 10. Said slots are so formed, that gravity maintains said rollers of the inking device in contact with each other and the printing roller 17. To prevent an excessive pressure by said rollers of the inking device on the printing roller, adjusting screws 25 are provided in the lower part of the slots, 20 which are in engagement with the bearings of the lower roller axle, that is, of the ink transferring roller.

The unprinted tape coming from the roll 14 over the roller 15, is passed over a guide roller 26, to cause a better engagement between the tape and the roller 15. The tape that passes between the roller 15 and the printing roller 17, becomes impressed by the printing roller 17. The so impressed tape 110 is then passed again over the roll 14, threaded through a guide 27, from where

it is passed between the feed roller 28 and the roller 29, co-acting therewith.

The feeding roller 28 has a part of its peripheral surface 30 rendered inactive by depressing the same, so that only a part of its periphery will feed. The length of this feeding surface of the feeding roller 28, is equal to the length of strips which the device is adapted to dispense. The feeding roller 28 is driven positively through a train of gears, of which a gear 31 is associated with the feeding roller 28 and which gear 31 is in mesh with an idler 32, meshing in turn with a gear 33, constrained to rotate with a drive shaft 34, a crank or handle 35 being attached to the shaft 34 for actuating the same, and therewith all other parts of the device.

A sprocket 36 is provided to turn with the shaft 34. An endless chain 37 connects the sprocket 36 with a sprocket 38, which sprocket is mounted to turn on a stud 39, mounted in the upper part of the frame side 9. Mounted to turn with the sprocket 38 is a gear 40, in mesh with a similar gear 41, rotatively mounted on a second stud 42. Mounted to turn with the gear 41 is a sprocket 43. The stud 42 extends across the frame and mounted to swing thereon, is an arm 44, which is central with the plane of the roll 14. The arm 44 carries a feeding roller 45, which is mounted to turn in the free end of the arm and preferably has an indented surface, so as to grip the tape. The feeding roller 45 has associated therewith, a sprocket 46 connected by an endless chain 47 with the sprocket 43. The feeding roller 45 is maintained against the tape roll 14, by a resilient member 48 mounted on the stud 42 and as the diameter of the roller decreases, the arm 44 is moved toward the axle 11. Although the diameter of the roll of tape decreases, the amount fed from the roll by the feeding roller 45 will be constant, in view of the fact that the same will travel the same length through each revolution of the driving shaft 34. The ratio of the sprockets constituting the constant feed, is such that a length of $5\frac{3}{8}$ inches is dispensed from the tape roll during each revolution of the crank or handle 35. The length of the effective lateral surface of the feed roller 28, is also equal to $5\frac{3}{8}$ inches. The train of gears from the drive shaft to the feed roller 28, is such that the feed roller feeds faster than the feeding roller 45, for the reason that the said feeding roller feeds constantly, while the feeding roller 28 feeds intermittently and consequently, to feed the same length, the intermittent feeds must be faster.

By providing an intermittent feed, the tape can be severed in strips during the time the feed of the tape is arrested. The length of strips severed by the cutting mechanism,

will be equal to the effective feeding surface of the feeding roller 28. The cutting mechanism is of a guillotine type, consisting of a blade 49, mounted to slide in grooves, provided in the frame sides 9 and 10. A support 50 also mounted between the frame sides, is adapted to co-act with the blade 49, which is maintained above the support against a stop 51, by means of spring-actuated plungers 52 carried by the frame sides. The blade 49 carries a roller 53, which contacts with a cam 54, mounted on the drive shaft 34, and whereby said blade is depressed against the support once during each revolution.

The tape coming from the intermittent feed to the cutting mechanism, is first passed through a guide 55 positioned between the feeding and cutting mechanism and in alignment with the support 50, so as to cause the tape coming from the intermittent feed, to slide over the support. Positioned in front of the support and bearing in the frame sides 9 and 10, is a moistening roller 56, which is partly immersed in water, provided in a receptacle 57 resting on the base 7. The moistening roller 56 is geared to the feed roller 28, so as to rotate in the same direction as the feed roller. A pressure roller 58 is provided on the top of the moistening roller, to maintain the gummed side of the tape against the moistening roller. A baffle plate 59 is also provided above the support 50 and between the support and the moistening roller, so as to direct the tape over the support to the moistening roller. During the cutting of the tape by the blade 49, the moistening roller 56 slips over the gummed side of the tape contacting therewith, but as soon as the tape is severed, the same is moved forward by the turning movement of the moistening roller.

The strips of tape coming from the moistening roller, fall on a delivery table or support 60, the length of which support, is less than the length of the strip severed from the tape; so that a portion of the severed strip 61, extends beyond the support 60 and can be bent as indicated in the dotted lines in Fig. 1 and thus be picked up from the support without the fingers contacting with the moistened, gummed side of the strip and without bringing any portion of the moistened, gummed surface of the strips into contact. The so picked up strip of gummed paper or tape, which carries the desired printing matter thereon, can be directly attached to a package to be sealed. The entire mechanism is provided with a casing 62, which has one side thereof removable, so as to facilitate the replacing of the rolls of tape 14. The casing is preferably attached to the base and has hinged portions 63 and 64 adjacent the moistening roller and the cutting mechanism, to facilitate the inspection of

parts, without necessitating the removal of the casing.

In Fig. 6 a modified structure of the device is shown. In this figure, the printing roller 17' is located above the co-acting roller 15'. The constant feed mechanism is not shown. When the roll of paper 14' has its gummed side unexposed, the winding of the tape 16' is shown in full lines in Fig. 6, and when the gummed side of the tape roll 14' is exposed, the winding of the tape 16'', would be such as shown in dotted lines in the same figure.

From the above description, it will be seen that my device comprises a support for a roll of tape, from which the tape is fed to a printing mechanism, the feeding of the tape from the roll being obtained by a constant feed mechanism toward an intermittent feed mechanism, the two mechanisms being adapted to feed a predetermined, constant length of tape. Co-acting with the intermittent feed mechanism, is a strip-cutting mechanism, which is adapted to support the tape at the time when the intermittent feed is not feeding the tape toward the cutting mechanism. The severed strips from the cutting mechanism, pass over the moistening roller and from there to a delivery table, from which they can be picked up by engaging the non-gummed side of the severed strips.

From the foregoing description, taken in connection with the accompanying drawings, the advantage of the construction and operation of the device shown, will be readily understood by those skilled in the art, to which the invention pertains and while I have described the principle of operation, together with the device, which I now consider to be the best embodiment thereof, I desire to have it understood that the device shown is merely illustrative and that such changes may be made as are within the scope of the appended claims.

Having thus described my invention, I claim as new and desire to secure by Letters Patent:

1. In a device of the class described, means for supporting a roll of gummed tape, a continuous-feed mechanism adapted to dispense tape from the roll, a printing device adapted to impress the tape while it is fed, an intermittent feed to advance the tape fed by the first-mentioned feed, a cutting mechanism to sever strips from the tape advanced by the intermittent feed, and a moistener for the gummed surface of the strips.

2. In a device of the class described, means for supporting a roll of gummed tape, a continuous-feed mechanism for dispensing a constant length of tape from the roll at any size of the roll, a printing device to impress the tape fed, an intermittent feed adapted to receive the tape fed from the roll and feed the same length of tape as fed

by the continuous-feed, a cutting mechanism for severing the strips from the tape advanced by the intermittent feed, and a moistener for the gummed surface of the strips.

3. In a device of the class described, means for supporting a roll of gummed tape, a roller engaging the tape on the roll, means for maintaining said roller against the tape on the roll, means for turning said roller through a predetermined distance 75 through each revolution of the device whereby a constant length of tape is unwound from the roll, a printing mechanism for impressing the tape, means for severing the tape into strips, and means for moistening the gummed side of the strips.

4. In a device of the class described, means for supporting a roll of gummed tape, a pivotally mounted arm, a roller carried by the arm, a resilient member forcing the arm against the tape on the roll, means for revolving the roller through a predetermined distance through each revolution of the device, whereby a constant predetermined length of tape is unwound 90 from the roll at each revolution, means for printing the tape, means for cutting the tape into lengths equal to the length fed by the roller during each revolution of the device, and a moistener for wetting the 95 gummed surfaces of the lengths of severed tape.

5. In a device of the class described, means for supporting a roll of gummed tape, a revoluble feed mechanism operable 100 continuously, including means for dispensing intermittently a predetermined length of tape from the roll, a cutting mechanism adapted to sever the length of tape fed, and a moistener for wetting the surface of the 105 gummed strips of tape.

6. In a device of the class described, means for supporting a roll of gummed tape, a printing device therefor, a continuous-feed mechanism adapted to dispense tape from 110 the roll, an intermittent feed for the tape fed by the constant feed, a cutting mechanism for severing the tape into strips, means synchronizing the movement of the intermittent feed and the cutting mechanism, 115 and a moistener for the gummed surfaces of the strips.

7. In a device of the class described, a moistener for wetting the gummed side of the strips, and a receiving table or support 120 for the strips, the length of the table being less than that of a strip, the front edge of said table forming the apex of a V beyond which the end of the advanced strip passes substantially as and for the purpose set 125 forth.

8. In a device of the class described, a moistener for wetting the gummed side of the strips and a receiving table for the moistened strips of a length less than the length 130

- of a strip, said table adapted to receive the gummed side of the strips, the front edge of said table forming the apex of a V over which the advancing end of a strip projects and whereby the projecting portion of the strip can be bent over the apex of the V in taking up the strip from the table without danger of bringing the moistened gummed parts into contact.
- 1.3 9. In a device of the class described, means for supporting a roll of gummed tape, a printing device, a continuous feed for dispensing tape from the roll to the printing device, a second feed for advancing intermittently the same length of printed tape for each cycle of the device as advanced by the continuous feed from the roll of tape, means for severing the tape into lengths as advanced by the intermittent feed, and a 15 moistening device for wetting the gummed surfaces of the severed strips.
10. In a device of the class described, means for supporting a roll of gummed tape, a printing device, a continuous feed mechanism to dispense tape from the roll, whereby the same is advanced through the printing device and impressed thereby, an intermittent feed for advancing the printed tape through the same length in each cycle 20 of the device as it is fed from the roll of

tape by the continuous feed mechanism, means for severing the tape into strips advanced by the intermittent feed, a moistener for wetting the gummed side of the strips, and a table for receiving the moistened tape, wherefrom the same can be picked up without engaging the moistened gummed part of the strips.

11. In a device of the class described, means for supporting a roll of gummed tape, 40 a pair of feed rolls for dispensing the tape from the roll, a guide for directing the tape from the roll to the feed rolls, one of said rolls having a portion of its feeding surface rendered inoperative whereby the feed of said rolls is intermittent, means for revolving the roll having a partially inoperative feed surface, a cutting mechanism for severing the tape into strips, means synchronizing the movement of the roll having the partially ineffective feeding surface and the cutting mechanism, and a moistener for the gummed surface of the strips.

In testimony whereof I have signed my name to this specification in the presence of 5 two subscribing witnesses.
